INVENTOR

OSCAR T. SPRAGGINS.
BY
A. H. Weatherford
ATTORNEY

UNITED STATES PATENT OFFICE.

OSCAR T. SPRAGGINS, OF MEMPHIS, TENNESSEE.

MAILING BOX.

Application filed January 19, 1924. Serial No. 687,239.

To all whom it may concern:

Be it known that I, OSCAR T. SPRAGGINS, a citizen of the United States, residing at Memphis, county of Shelby, and State of

5 Tennessee, have invented certain new and useful Improvements in Mailing Boxes, of which the following is a full, clear, and exact description, such as will enable anyone skilled in the art to make and use the same.

10 My invention relates to improvements in paper boxes, especially adapted for mailing purposes and has for its objects to provide;

First, a box adapted to be readily fastened or sealed and when opened, as readily re-

15 fastened or re-sealed.

Second, to provide such a box adapted to be substantially rigid against compression or distortion such as would ordinarily be encountered in the mails and one which is ca-

20 pable of economic manufacture; and

Third, to provide such a box wherein a smooth or continuous surface is provided on that side which opens whereby when an address label is pasted thereon it may lie flat

25 and smooth, and the box be effectively sealed thereby.

I accomplish these objects as will be more fully hereinafter set out in the drawings, specifications and claims.

30 In the drawings:

Fig. 1 is a perspective view of one form of the box open for the insertion or removal of objects therefrom.

Fig. 2 is a similar view of the same box with a drawer or inside container therein.

Fig. 3 is a similar view of the box closed with an address label pasted thereon providing additional sealing means.

Fig. 4 is a developed view of the box flat-

40 tened out.

Fig. 5 is a perspective view of a slightly modified form of the box with an inside container and having a reinforced closing means providing additional stiffening and

45 also providing means for fastening the box without other sealing than the address label.

Fig. 6 shows a similar view of a further modification in which a complete outer box is hinged to and adapted to be closed over an inner box, and sealed in the identical manner shown in Figs. 1, 2 and 3.

Fig. 7 is a fragmentary perspective of a modification of the flaps 11 shown in Fig. 5.

50 Referring now to the drawings in which the various parts are indicated by the same numerals in all the views, the box shown

in Figs. 1 to 4 comprises a bottom 1, sides 2 and 3, and a top 4 with an extra side 2^a gummed as indicated by the lining thereon, which is adapted to fold over and be sealed 60 against the outer surface of the side 2 forming thereby a rectangular open ended box. 5 are flaps adapted to fold inward at both ends of this open section and 6 are ends 65 each having an extension member 7 gummed as indicated by the lining thereon adapted to fold over and seal against the top 4 of the box, both of these members being shown sealed in Fig. 3 and one only in Figs. 1 and 2.

In Fig. 3, 8 is an address label sealed over the ends of the members 7 and to the sides of the box, the underside of this label being gummed for that purpose. If desired this label may be placed longitudinally instead 75 of transversely as shown.

In Fig. 2, 9 is an inner liner shown in this case as open at both ends.

It will be especially noted in this box that when the flaps 5 are folded inward they 80 form an additional brace against lateral distortion of the box. If desired, the inner box 9 may be an ordinary box with sides and ends and an open top. In Fig. 5 I show a modified form of the box having a top 85 4 and sides, only one of which, 2, shows in the view and having a bottom which likewise does not show. This box also has flaps 5 and an inner box 9^a which may, if desired, be open ended as shown in Fig. 2, or with 90 closed ends and an open top as here shown.

This box is also provided with ends 6 and extension members 7^a and 7^b. These members may be gummed as shown in Figs. 1, 2 and 4 in which case this box is identical 95 with the exception of the inner container with that shown in Figs. 1, 2 and 3. In this view however, I show the member 7^a sealed to a reinforcing member 10 which is

100 preferably of somewhat heavier paper and may be, if desired of the well known corrugated paper board, which gives the box material added strength. The other member 7^b is provided with laterally extending flaps 11 which are adapted to be folded inward as shown and which form a pocket into which the outer end of the reinforcing member 10

105 may be slipped to form a closure for the box. The flap 7^a may also be provided with similar flaps if desired in order that the closure members may line up smoothly over the top of the box. When this is done, the 110

members 7^A and 7^B form a smooth surface over which a label may be pasted as shown in Fig. 3 which label, when so pasted will form an efficient sealing means for the box.

In Fig. 7 I show the flaps 11 each provided with a pair of extending fasteners 13 which fasteners are gummed as indicated by the lining thereon and may be used to seal the flaps 11 to the sides 2-3 and bottom 1 of the box. In such case the flaps 11 are not folded in to form a pocket but are allowed to extend as shown in Fig. 7 and come against the sides of the box. Two only of the gummed flaps 13 are shown attached to each flap 11, but any number desired may be provided. In use all these except the outer ones are folded against the inside of the flaps 11, and the outer ones are sealed to the bottom of the box. When these have been destroyed by opening the box, new sets may be used as long as they last.

In Fig. 6 I show a further modification in which an open top box having sides 2 and 3 and closed ends 12, is provided with ends 6 extending outward from the bottom thereof as in the other boxes, and is also provided with gummed extension members 7, the gum on which being on the under side is not visible. It is however, provided with an additional box having a top 4, sides 2^A and ends 12^A which is sealed to the under side of one of the extension members 7. It may or may not be sealed to the end 6 but is preferably not so sealed. When this box is closed that extension member 7 which is loose is as in the other cases, sealed against the top 4 thereof and as in the other cases, when so sealed, forms a smooth surface for the reception of an address label.

It will be understood that while I prefer to use an address label, that any of these boxes may be sealed without the use thereof. If however, this should be done in case of the box shown in Fig. 5, it would be necessary to gum the under side of the extension 7^B and if desired also, the contiguous sides of the flaps 11.

It will also be seen that various minor modifications may be made without departing from the spirit of my invention. One of these changes being to make the extension members 7 the full length of the top 4 so that when folded over and sealed, they form a triple top for the box such as is obtained in slightly different fashion by the extension members 7^A and 7^B and the reinforcing member 10 of Fig. 5.

It will also be especially understood that while I have referred herein to the top 4 and bottom 1, that when this box is turned over

these become respectively the bottom and the top and that I do not intend by the use of these terms to in any way, limit myself in that respect.

I also desire it to be understood that I 65 reserve the right to change the construction of my invention as long as doing so comes under the appended claims.

Having now fully described my invention, what I claim and desire to secure by Letters 70 Patent of the United States is:—

1. A paper box comprising sides, a top, a bottom, foldable ends, members extending therefrom, a reinforcing member substantially the size of the top of said box sealed 75 to one of said extension members, flaps extending laterally from the other of said extension members, adapted to be folded inward to form a pocket for said reinforcing member, and foldable members integral 80 with the sides of the box adapted to be folded across the ends of the box before the foldable ends thereof are folded and sealed to provide stiffeners for the box against collapse.

2. A paper box comprising sides, a top, a bottom, foldable ends, members extending therefrom, a reinforcing member substantially the size of the top of said box, sealed to one of said extension members, flaps extending laterally from the other of said extension members, adapted to be folded inward to form a pocket for said reinforcing member.

3. A paper box comprising sides, a top, a 95 bottom, foldable ends, members extending therefrom, a reinforcing member substantially the size of the top of said box sealed to one of the said extension members, a pocket on one of said extension members 100 adapted to receive an opposite member, and foldable members integral with the sides of the box adapted to be folded across the ends of the box before the foldable ends thereof are folded and sealed, to provide stiffeners 105 for the box against collapse.

4. A paper box comprising sides, a top, a bottom, foldable ends, members extending therefrom, a reinforcing member substantially the size of the top of said box sealed 110 to one of said extension members, and a pocket on one of said extension members adapted to receive an opposite member.

In testimony whereof I have hereunto set my name.

OSCAR T. SPRAGGINS.
